BOOKMARK

George V. Zumft, Stony Brook, N. Y., assignor,
by direct and mesne assignments, to The
X-Sellent Novelty Company, New York, N. Y.

Application March 9, 1938, Serial No. 194,744

2 Claims. (Cl. 116—119)

This invention relates to devices used by students and other readers of books by which a predetermined page may be referred to, such devices being known under the generic term of book-
marks.

The more common form of bookmarks consist of ribbons, tapes, cards, paper strips and similar thin flat articles disposed between the pages of a book selectively, but which are liable to loosening and consequent loss of pre-selected position.

It is therefore an object of this invention to provide a bookmark having means by which it may be anchored to the book cover, preventing displacement of the place-distinguishing marker.

Another purpose is to produce a bookmark having a marker leaf of high flexibility and resiliency, permitting turning of the book leaves, successively moving from one position to the next, without attention or effort on part of the reader, automatically as each leaf or page is turned.

Another purpose is to produce a bookmark having a marker leaf of high flexibility and resiliency, permitting turning of the book leaves, successively moving from one position to the next, without attention or effort on part of the reader, automatically as each leaf or page is turned.

These objects and others, such as pleasing appearance, facility of operation and moderate cost of construction, are attained by the novel design, construction and combination or parts herein-
after described and illustrated in the annexed drawing, constituting an essential component of this disclosure, and in which:

Figure 1 is a perspective view showing one form of an embodiment of the invention.

Figure 2 is a similar view of a modified construction of the bookmark illustrating its application.

On Figure 2 of the drawing a representation of an open book of conventional type is shown, consisting of a cover 15 having a plurality of leaves or pages 16, one of which, as 17, is partially raised from the others as in the act of turning.

A spring clip, generally designated by the number 20, consists preferably of a thin metallic plate 21, bent upon itself reentrantly to present a curved loop 22, the underlying resilient clamp element 23, extending from the loop, being down-turned at its smoothly rounded edge 24.

The plate 21, which is adapted to be entered between the cover 15 and leaves 16, extends in advance to a considerable distance beyond the clamp plate 23, as best seen in Figure 1, and is provided with a rectangular aperture 25 adjacent its outer edge, a similar aperture 26 being sheared from the plate, near the loop 22, the material

sheared in forming the aperture being upturned angularly to form a brace element 27.

A strip of resilient material 30 as Celluloid is passed through the aperture 26, under the main central portion of the plate 21, and upwardly through the aperture 25, the edges of the strip being guided by the end edges of the apertures.

That part of the strip extending outwardly above and beyond the aperture 26 is curved to reach, in spaced relation, over the plate 21, the curved portion 31 being materially supported by the brace 27, while its continuation 32 is disposed normally parallel with the main portion 30.

The marker 35 is made of very thin, resilient material, as sheet Celluloid, and of any preferred profile, preferably reduced in width towards its point 36, which is adapted to enter between the leaves of the book at any desired place.

As shown in Figure 1 the marker is secured, at its wider end portion, by a tubular rivet 37 to the forwardly extending end 32 of the strip 30, in such manner as to permit turning on the rivet, thereby permitting the indexing point 36 to swing relative to a definitely selected position on the page.

In Figure 2 the marker 35 is provided with a series of slots 38 through which the end of the support strip 32 may be interengaged in such manner as to permit of separation and also longitudinal adjustment.

It is to be understood that the marker 35 is so thin, flexible and delicately mounted on the resilient support strip 32, that, upon turning a page of the book, it will be raised by movement of the page and thereafter spring again into operative position without being operated by hand.

Having described the invention, what is claimed as new and sought to secure by Letters Patent is:

1. A bookmark comprising a resilient marker, a flexible mount, a connection between said marker and mount, a spring clamp to engage the cover of a book, said mount slidably engaged by said clamp, and a reinforcement for said mount integral with said clamp.

2. A bookmark comprising a spring-clip body portion having a sloping leg portion adapted to be positioned between the book cover and adjacent page, said portion having a pair of transverse slits therein, a resilient marker element 50 threaded in said slits, a tab projecting from said body portion and engaging said marker element deflecting the same in a direction toward the pages for enabling it to droop under its own weight to a position overlying the page of the book.
